UNITED STATES PATENT OFFICE.

JAMES ERNEST DALEY, OF PORT ANSON, ONTARIO, CANADA.

SILENCER AND CONDENSER FOR GASOLENE-ENGINES.

1,228,185.

Specification of Letters Patent. Patented May 29, 1917.

Application filed May 24, 1916. Serial No. 99,697.

To all whom it may concern:

Be it known that I, JAMES ERNEST DALEY, a citizen of Canada, residing at Port Anson, in the Province of Ontario, Dominion of Canada, have invented a new and useful Silencer and Condenser for Gasolene-Engines; and I do hereby declare the following to be a full, clear, and exact description of the invention, such as will enable others skilled in the art to which it appertains to make and use the same.

The present invention relates to an improved silencer and condenser for receiving the exhaust gases of an internal combustion engine, the object of the invention being to provide a device of this character which embodies novel features of construction whereby back pressure is avoided and the gases permitted to expand and be discharged in a practically noiseless manner.

Further objects of the invention are to provide a device of this character which is comparatively simple and inexpensive in its construction, which provides successive expansion chambers having resilient walls which are adapted to flex in and out under the pulsations of pressure and thereby permit the exhaust gases to be acted upon without producing back pressure in the engine, and which has no delicate parts such as would become clogged with soot and interfere with the proper operation of the silencer after a very brief period of use.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:

Figure 1 is a longitudinal sectional view through a silencer and condenser constructed in accordance with the invention, showing the same as applied to the hull of a vessel.

Fig. 2 is a transverse sectional view through the same.

Corresponding and like parts are referred to in the following description and indicated in all the views of the drawings by the same reference characters.

Referring to the drawings, which illustrate one embodiment of the invention, the

reference character 1 designates the planking of the hull of a marine vessel, fragmentary parts only of which are shown. Arranged upon the inside of the hull is an outer casing or water jacket 2, preferably cylindrical in shape, the side of the said outer casing which fits against the planking 1 being formed with a longitudinal slot 3 which extends the full length of the casing and registers with a corresponding slot in the planking 1. An inner casing 4, also preferably cylindrical in shape, is arranged within the outer casing 2, a water space 5 extending completely around the inner casing 4. Arranged within the inner casing 4 is a series of resilient partition members 6 which subdivide the same into a series of successively intercommunicating chambers 7, 8, 9, 10 and 11, the inner expansion chamber 7 receiving the exhaust gases direct from the engine through the pipe 12 which enters one end of the casing 4, while the gases are finally discharged from the outer chamber 11 through the discharge pipe 13. Each of the resilient partitions 6 may be conveniently formed by rolling a piece of sheet metal into substantially cylindrical shape, the edges of the rolled sheet having an overlapping and slightly spaced relation, and the ends of the rolled sheets being slightly spaced from the ends of the inner casing 4. The backs of the rolled sheets 6 are engaged by bolts 14 which pass through the casing 4 and water jacket 2, suitable spacing collars 15 being interposed between the various members to hold them in a properly spaced relation. Nuts 16 are screwed upon the extremities of the bolts 14 and provide a means for clamping all of the parts securely together. Arms 17 may be provided at suitable intervals between the inner casing 4 and the water jacket 2 to hold the inner casing properly centered within the water jacket. The exhaust pipe 12 is preferably larger in diameter than the discharge pipe 13, and the overlapping of the free edges of the rolled partitions 6 preferably increases successively from the inner partition 6 to the outer partition 6.

There will be violent pulsations of the exhaust gases of the engine as they enter the inner expansion chamber 7 through the exhaust pipe 12. The resilient walls 6 of this inner expansion chamber 7 will be flexed in and out by the variations of pressure, while the gases will escape through the overlap-

ping edges of the inner partition 6, and around the ends thereof, into the next expansion chamber 8. Here the operation will be repeated, although the pulsations will be less violent. The exhaust gases will thus pass successively through the various expansion chambers 7, 8, 9, 10 and 11, the resilient walls of each of the inner chambers flexing to accommodate the variations or 10 pulsations of pressure, and these pulsations of pressure becoming successively less violent in the different expansion chambers, until the gases are finally discharged through the pipe 13 in a low pressure and 15 nearly constant stream. When the exhaust gases reach the outer expansion chamber 11 they will be brought into contact with the walls of the casing 4 which are cooled by the surrounding water, so that a practically 20 noiseless discharge of the exhaust gases is obtained, and practically no back pressure is produced upon the engine.

Having thus described the invention, what I claim as new and desire to secure by Letters Patent, is:—

1. A silencer and condenser for internal combustion engines, including an outer casing having an inlet and an outlet, a rolled resilient sheet arranged within the outer 30 casing and rigidly supported therein at an intermediate point in its length, the edges and ends of the rolled sheet being free so that the ends of the sheet will flex under the pulsations of pressure.

2. A silencer and condenser for internal combustion engines, including an outer casing having an inlet and an outlet, a rolled resilient sheet arranged within the outer casing and having the free ends thereof spaced 40 from and overlapping each other, said rolled sheet being rigidly supported at an intermediate point in its length with the edges and ends thereof left free so that the ends

of the sheet will flex under pulsations of pressure.

3. A silencer and condenser for internal combustion engines, including an outer casing having an inlet and an outlet, a series of rolled resilient sheets nested within each other and arranged within the outer casing 50 to provide a succession of expansion chambers through which the exhaust gases pass before being discharged, the free edges of the rolled sheets overlapping each other and having a spaced relation, and means for 55 rigidly supporting the rolled sheets at intermediate points in the length thereof with the edges and ends of the sheets free to flex, said ends of the sheets flexing under the pulsations of pressure when the device is in operation.

4. A silencer and condenser for internal combustion engines, including an outer casing having an inlet and an outlet, a series of rolled resilient sheets nested within each 65 other and arranged within the outer casing to provide a succession of expansion chambers through which the exhaust gases must pass before being discharged, the free edges of the rolled sheets overlapping each other 70 and the overlapping of the edges increasing successively from the inner rolled sheet to the outer rolled sheet, and means for rigidly supporting the rolled sheets at intermediate points in the length thereof with the ends 75 thereof free to flex, said ends of the rolled sheets flexing under the pulsations of pressure when the device is in operation.

In testimony whereof I have signed my name to this specification in the presence of 80 two subscribing witnesses.

JAMES ERNEST DALEY.
